JOSEPH ROCH BRIEN, OF MONTREAL, QUEBEC, CANADA, ASSIGNOR OF ONE-FOURTH TO
HENRI STE MARIE AND EMERY STE MARIE, BOTH OF MONTREAL, CANADA

OIL BURNING SYSTEM

Application filed April 8, 1929. Serial No. 353,469.

The present invention pertains to a novel oil burning system designed particularly for the combustion of oil as a fuel in domestic and industrial installations.

5 The invention lends itself particularly to use in conjunction with a boiler heated by means of an oil burner, and in such an arrangement the steam generated by the boiler, as well as the hot water produced therein, are utilized in the operation of the device. 10 More specifically, the steam is conducted from the boiler to the mixing chamber of the burner in order to atomize the oil, and the hot water is used for warming the oil 15 and maintaining it in a heated condition while flowing from the tank to the burner.

The invention is fully disclosed by way of example in the following description and in the accompanying drawings in which;—

20 Figure 1 is an elevation of the system showing the boiler in longitudinal section;

Figure 2 is a longitudinal sectional view of the burner, and

Figure 3 is a detailed section on the line 25 3—3 of Figure 1.

Reference to these views will now be made by use of like characters which are employed to designate corresponding parts throughout.

In Figure 1 is shown a boiler 1 which, for 30 the purpose of the present invention, is preferably equipped with a steam dome 2. The boiler is encased in a furnace 3 having a grate 4 disposed beneath the boiler. On the grate is supported a sloping bed 4' of ashes 35 or the like for spreading the flame from the burner which will be presently described.

40 Into the forward end of the furnace, slightly above the grate, is inserted an oil burner casing including a mixing chamber 5 and 45 from which depends an integral air inlet 6 open to the atmosphere exteriorly of the furnace.

The outer end of the member 5, 6 is open at 7 for admission of air. A nozzle 8 is 45 passed through the upper part of the burner and is directed towards the mixing chamber, while into the outer end 7 is passed a nozzle 9 connected by a pipe 10 to the steam dome 2 and having a valve 11 for control 50 purposes. A by-pass 8' connects the nozzle

8 to the pipe 10 at a point below the valve 11.

At a convenient position removed from the boiler is disposed an oil supply tank 12 for containing the oil to be delivered to the mixing chamber 5. An oil pipe 13 extends 55 from the top of the tank and enters the by-pass 8'. This pipe has a check valve 14 for preventing back flow to the tank.

A hot water pipe 15 extends from the water space of the boiler 1 into the oil tank 12 and 60 to a considerable depth therein. A portion of the water pipe passes through the oil pipe 13 as clearly shown in Figures 2 and 3. The hot water pipe is equipped with a reducing valve 16 to diminish the pressure and with a 65 safety valve 17 adjusted to open in the event that the valve 16 fails. The pipe 15 is also provided with cut-off valves 18 and 18' at opposite sides of the valves 16 and 17.

In the operation of the device as thus far 70 described, hot water under pressure passes from the boiler through the pipe 15 to the top of the oil tank 12 and exerts a pressure on the oil therein. Under this pressure the oil is forced through the oil pipe 13, into the by- 75 pass 8' and through the nozzle 8 into the mixing chamber 5. It will be seen that the by-pass 8' has valves 19 and 20 at opposite sides of the oil pipe 13. In normal operation the valve 19 is closed and the valve 20 open. 80 At the same time steam under pressure passes from the dome 2 through the pipe 10, the valve 11 being open, and to the nozzle 9 and mixing chamber 5.

The injection of steam into the chamber 85 5 causes a draft of air through the inlets 6 and 7 to the mixing chamber 5 as indicated by the arrows in Figure 2. The steam mixes with this air and humidifies it, and finally an 90 intimate mixture of oil, steam and air of the proper proportions for combustion is formed in the mixing chamber and delivered in ignited condition to the bed 4'. The oil, moreover, prior to reaching the nozzle 8, is heated by contact with hot water in the tank 12 and 95 further by flowing around a portion of the pipe 15. This arrangement makes it possible to position the oil tank at any desired or convenient distance from the burner and yet 100 maintain the heated condition of the oil by

its passage around the enclosed portion of the pipe 15.

The system is controllable in all respects by the valves 11, 18, 18', 19 and 20 and is 5 completely shut down by closing all of these valves. It will be apparent that the flow of steam, hot water and oil is regulated by the valves 11, 18 and 20 respectively. The by-pass 8' may be cleaned at will by opening 10 both valves 19 and 20, thus allowing a charge of steam to flow through the by-pass and the nozzle 8.

Although a specific embodiment of the invention has been illustrated and described, it 15 will be understood that various alterations in the details of construction may be made without departing from the scope of the invention as indicated by the appended claim.

What I claim is:—

20 In an oil burning system, a boiler, a burner beneath said boiler and including a chamber and an air inlet, an oil supply tank, an oil nozzle in said burner, an oil line connecting said nozzle to the upper part of said tank, 25 a hot water pipe connecting said boiler to a lower level in said tank and having a portion passing through said oil line, a steam dome on said boiler, a steam nozzle in said burner, a steam line connecting said steam 30 nozzle to said dome, a by-pass from said steam line to said oil nozzle, and a valve in said by-pass.

In witness whereof I have hereunto set my hand.

35 JOSEPH ROCH BRIEN.
